FUEL FEEDING MECHANISM FOR BURNERS

Walter Olsen, Albert Lea, Minn., assignor to
American Gas Machine Company, Albert Lea,
Minn., a corporation of Delaware

Application October 24, 1932. Serial No. 639,269

6 Claims. (Cl. 158—81)

This invention relates to fuel feeding mechanism for such devices as stoves, lanterns, irons, heaters etc., using liquid hydrocarbon fuel such as gasoline which is vaporized and burned.

5 It is the general object of the invention to provide, for such devices, novel fuel feeding mechanism which is cheap in construction and simple in operation to initially supply an ignitable and free burning mixture of air and liquid fuel from 10 an air pressure fuel tank to the burner to permit starting of the burner without preheating of a generator tube upon which the burner plays and then after the generator tube is heated up, to supply only liquid fuel from the tank to the generator tube to maintain the burner in constant 15 operation without exhausting air from the tank.

It is a further object to provide such fuel feeding mechanism which, as it is used for the initial lighting of a burner, will accurately measure both 20 the liquid fuel and air admitted to the generator tube so as to maintain an accurate ratio between the air and liquid fuel.

Another object is to provide such fuel feeding mechanism which, while the burner is in continuous 25 operation, will permit the supply of air to the generator tube to be exceedingly rapidly cut off after the burner has been initially lit and the generator tube has been heated.

The objects and advantages of the present invention will more fully appear from the following description, made in connection with the accompanying drawing, wherein like reference characters refer to the same or similar parts throughout the various views, and, in which, 35 Fig. 1 is a plan view showing an embodiment of my novel fuel feeding mechanism applied to a stove;

Fig. 2 is a vertical section taken through the tank of the stove and through the valve body located therein, the tubes located below the valve body not being shown in section;

Fig. 3 is an enlarged detail view showing a portion of the valve body in vertical section;

Fig. 4 is a view on an enlarged scale taken in vertical section through the upper portions of the tubes located below the valve body; and

Fig. 5 is a view taken similarly through the lower portions of these tubes.

Referring to the drawing, portions of a stove 50 adapted for the burning of vaporized gasoline are illustrated. This stove includes a frame 6, an apertured top plate 7, a liquid fuel tank 8 adapted to contain gasoline under air pressure and secured to the frame 6, a main burner 9, a generator tube 10 located over the burner and on

which the flames from the burner may play, a mixing chamber 11, into which the generator tube 10 leads and a conduit 12 leading from the mixing chamber 12 to the burner 9. Discharge of fuel from the generator tube 10 is controlled by a handle equipped valve 13. These parts are all of standard construction and need not be further described.

In accordance with the present invention, there is mounted in the top of the tank 8 a valve body 14 having a vertical passage 14a therethrough within which a valve seat 15 is formed. Above the valve seat 15 the body 14 is provided with a lateral extension 16 within which a discharge passage 17 is formed. A conduit 18 connected by a suitable coupling to the extension 16 runs from adjacent the tank 8 to the generator tube 10 and is suitably connected to the tube to afford communication between the passage 17 and the tube. A valve stem 19 having a wheel 20 at its upper end projects from above the body 14 downwardly into the vertical passage 14a of the body and is equipped at its lower end with a valve 21 which may be seated against the seat 15. The stem 19 above the valve 21 is equipped with an enlarged screw-threaded portion 22 which engages with an internal screw-threaded portion in the valve body. A suitable packing gland 23 fitting about the stem 19 engages with the valve body 14 to prevent leakage through the upper end of the vertical passage 14a. It will be seen that by turning the wheel 20 in one direction, the valve 21 may be withdrawn from the seat 15, while by turning the wheel 20 in the opposite direction the valve may be caused to engage its seat. Above the valve seat 15, the vertical passage 14a is enlarged to accommodate the stem 19 and at the same time to afford communication between the passage 17 and the part of the vertical passage 14a below the valve seat 15 when the valve 21 is raised.

An inner or primary liquid fuel supply tube 24 of an external diameter less than the diameter of the passage 14a below valve seat 15, is secured at its upper end to the central portion of the valve 21 and this tube 24 projects downwardly through the passage 14a to a point adjacent the bottom of the tank 8 well within the liquid fuel space of the tank. The upper end of the inner tube 24 is sealed by its connection with the valve 21, while the lower end of the tube 24 is open, the outer edge of the lower end of the tube preferably being beveled slightly as shown in Fig. 5. An intermediate or feed tube 25 of considerably greater diameter than the tube 24 is mounted at

its lower end in the lower end of the valve body 14 to communicate with the lower end of the passage 14a and this intermediate tube 25 surrounds the inner tube 24 and projects downwardly into the tank 8 into the liquid fuel space thereof to a point adjacent but slightly above the lower end of the inner tube 24 when the stem 19 is turned to such a position that the valve 21 is seated. The intermediate tube 25 is crimped inwardly to form, or is provided with, a part closure 26 at its lower end having an opening therethrough of such size as to permit the passage of the lower end of the inner tube 24 through the opening. An outer or air supply tube 27 of considerably greater diameter than the intermediate tube 25 surrounds the intermediate tube in coaxial relation, is secured and sealed to the tube 25 at its lower end and projects upwardly from the liquid fuel space of the tank to terminate short of the lower end of the valve body 14 within the compressed air space of the tank 8. The outer tube 27 is, of course, open at its upper end. Preferably a strainer comprising a sleeve 28 carrying a fine mesh screen 29 at its lower end is secured to the lower end of the outer tube 27 as by a screw-threaded connection.

The inner or primary liquid fuel supply tube 24 is provided with a small orifice 24a located preferably, although not necessarily, a short distance below the valve body 14. This orifice 24a is carefully drilled and regulated in size so that it will equal in size the orifice (not illustrated) leading from the generator tube 10 to the mixing chamber 11. Adjacent the lower end of the intermediate or feed tube 25, a pair of diametrically opposed air openings 25a are provided in the tube to afford communication between the outer or air supply tube 27 and the feed tube 25. These openings 25a are also carefully regulated in size relative to the orifice 24a as will be later explained.

Operation

In starting the stove, valve 13 will first be opened whereupon the wheel 20 will be given from one-fourth to one-half a turn sufficient to cause the valve 21 to be raised from its seat 15 without raising the lower end of the primary liquid fuel supply tube above the closure 26. Of course, the gasoline in tank 8 will have previously been placed under considerable air pressure and as the valve 21 is raised, gasoline will pass into the tube 24 to discharge in a fine regulated stream from the orifice 24a into the feed tube 25 well above its lower end. As the upper end of the outer air supply tube 27 is open and located within the air space of the tank 8, air will be forced downwardly through the tube 27 and through the openings 25a into the feed tube 25 and this air will move upwardly through the feed tube until it reaches the level of the orifice 24a. At this point the gasoline discharged from the orifice 24a will mix with the air and form a mixture of air and gasoline which runs through the lower part of passage 14a, passage 17 and conduit 18 to the generator tube 10 from whence it will be discharged into the mixing chamber 11 to mix with additional air and thence be carried through the conduit 12 to the burner 9. A combustible mixture will be produced at the burner 9 and this burner may be immediately lit after the valve 21 has been initially raised. The size of the air openings 25a is so regulated relative to the size of the orifice 24a that a clean free burning flame will be produced as the burner 9 is lit.

The size of the tube 24 is such that the level of liquid fuel in the tank 8 will have little or no effect on the passage of gasoline through the tube 24 and the discharge of gasoline from the orifice 24a in a regulated stream. The air openings 25a are so related in size to the discharge orifice of the generator tube 10 that air alone running through the openings 25a and supplied to the generator tube is not sufficient for the capacity of discharge from the generator tube. Consequently, when the valve 21 is first raised, a slight vacuum will be created in the tube 25 relative to the pressure of air within the tank 8 and in the tube 27 and this vacuum will cause the gasoline to move in a fine stream from the tube 24 through orifice 24a into tube 25.

The flame from the burner 9 will, of course, play upon the generator tube 10 and heat up this tube to cause vaporization of the liquid fuel therein whereupon due to the small size of the orifice leading from the generator tube 10 to the mixing chamber 11, back pressure will be created in the generator tube and in the conduit 18 to retard the upward movement of air through the feed tube 25 by reason of an accumulation of gasoline discharged from the orifice 24a in the feed tube 25. Some air, however, will continue to pass upwardly through the feed tube 25 to the generator tube 10. After the burner 9 has been operated for a short time such as the period of a minute, or until the generator tube is quite hot, the wheel 20 may be turned to raise the valve 21 farther from its seat 15 and at the same time carry the lower end of the primary liquid fuel supply tube 24 above the closure 26. As this occurs, gasoline will quickly rush into the lower end of the feed tube 25 through the now unrestricted opening in the closure 26 whereupon the level of gasoline within the feed tube 25 will quickly raise to seal off the air openings 25a and cause gasoline to rise in the outer air supply tube 27 above the level of these openings. Pure gasoline will then pass from the feed tube 25 to the generator tube 10 and the burner 9 may be continuously operated without depletion of the air supply in the tank 8.

It will be seen that an exceedingly simple feeding mechanism has been provided which will initially supply an instantly ignitable and free burning mixture of air and gasoline to the burner without necessitating preheating of a generator tube and which after the generator tube has heated will supply only gasoline to the generator tube to maintain the burner in constant operation without exhausting air from the fuel supply tank. Although the present fuel feeding mechanism has been illustrated and described in connection with a stove using gasoline as its fuel, it will be readily understood that the fuel feeding mechanism can be used with any type of equipment burning any liquid fuel that will vaporize. In particular it is contemplated that the mechanism of the present invention may be used with lanterns, irons, heaters, etc.

The present fuel feeding mechanism permits the burner to burn with an exceedingly clean flame at the time of starting the burner for the reason that both the air and liquid fuel are accurately measured. As the ratio used in starting has no effect on the burning of the burner after the valve 21 is widely opened, a leaner mixture may be provided for starting the stove than usually required in starting such burners. The size of the opening through the closure 26 at the lower end of the feed tube 25 is not involved in

producing the starting mixture and, therefore, this opening may be quite large in size to supply sufficient gasoline or other liquid fuel to quickly seal off the air passing through the air openings 25a in starting even when the air in the fuel tank is under high pressure. The operation of the feed mechanism is consistently satisfactory because the changes in the ratio of liquid fuel and air in starting brought about by variations in liquid fuel levels in the tank and air pressures in the tank are slight because the liquid fuel and air as admitted to the generator tube are accurately measured.

The present invention has been amply and successfully demonstrated in actual practice. The construction including the three tubes 24, 25 and 27 together with the strainer sleeve 28 is such that these parts can all be readily withdrawn from the tank 8 with the valve body 14 for cleaning or repair. The parts are few and simple.

It will, of course, be understood that various changes may be made in the form, details, arrangement and proportions of the various parts without departing from the scope of the present invention, which generally stated, consists in the matter shown and described and set forth in the appended claims.

What is claimed is:—

1. The combination with a liquid fuel tank adapted to contain liquid fuel under air pressure, of a fuel feeding mechanism for a burner, comprising a primary liquid fuel supply tube disposed within the tank, open at its lower end and closed at its upper end and having its lower end within the liquid fuel space of said tank, means operable externally of said tank for raising and lowering said tube slightly, a feed conduit mounted in said tank and extending into the liquid fuel space of said tank to a point slightly above the lower end of said tube when said tube is lowered to its extreme position, said conduit having an apertured closure at its lower end through which said tube normally extends to fill said aperture, said tube as it is raised being withdrawable from said aperture, said tube having an orifice above its lower end communicating with said conduit, said conduit having air openings therein adjacent its lower end below said orifice, means affording communication between the air space of said tank and said air openings and means affording a passage from said conduit to the exterior of said tank.

2. The combination with a liquid fuel tank adapted to contain liquid fuel under air pressure, of a fuel feeding mechanism for a burner, comprising a valve body mounted in said tank and having an inlet and an outlet and a valve seat intermediate said inlet and outlet, a valve operable externally of said body and movable to and from said seat, a primary liquid fuel supply tube connected with said valve, running downwardly into the liquid fuel space of said tank, closed at its upper end, open at its lower end and having a discharge orifice spaced above its lower end, a supply conduit communicating with the inlet of said body, running into the liquid fuel space of said tank and having an apertured closure at its lower end slightly above the lower end of said primary tube when said valve is seated and through which aperture said primary tube normally extends to substantially fill the same and prevent direct passage of liquid fuel to said conduit through said aperture, said orifice discharging into said conduit, said conduit having an air opening below said orifice and means commun-

cating said air opening with the compressed air space of said tank whereby said valve may be raised a short distance from its seat without withdrawing the lower end of said primary tube from said aperture and said valve may be raised further from said seat to withdraw said primary tube from said aperture.

3. The combination with a liquid fuel tank adapted to contain liquid fuel under air pressure, of a fuel feeding mechanism for a burner, comprising a primary liquid fuel supply tube disposed within the tank, open at its lower end, closed at its upper end and having its lower end within the liquid fuel space of said tank, said primary tube having a discharge orifice spaced upwardly from its lower end, means operable externally of said tank for raising and lowering said primary tube slightly, a feed tube mounted in said tank and through which said primary tube extends, said feed tube extending into the liquid fuel space of said tank to a point slightly above the lower point of said primary tube when said primary tube is lowered to its extreme portion and said feed tube having an apertured closure at its lower end through which said primary tube normally extends to fill said aperture, means affording communication between the upper end of said feed tube and the exterior of said tank, said primary tube as it is raised being withdrawable from said aperture, said feed tube having an air opening adjacent its lower end below said orifice and means affording communication between the air space of said tank and said air opening.

4. The combination with a liquid fuel tank adapted to contain liquid fuel under air pressure, of a fuel feeding mechanism for a burner, comprising an inner, a medial and an outer tube assembled in coaxial relation and disposed within said tank, means affording communication between said medial tube and the exterior of said tank, said medial tube having an apertured closure at its lower end disposed within the liquid space of said tank and also having an air opening therein adjacent its lower end, said outer tube being sealed at its lower end to said medial tube and having an open upper end extending into the air space of said tank, said inner tube being closed at its upper end and projecting downwardly through the apertured closure of said medial tube to extend normally slightly below the lower end of said medial tube to normally fill said aperture, said inner tube having an orifice communicating with said medial tube above said air opening therein, and means operable externally of said tank for raising said inner tube to such a point that the lower end of the inner tube is carried out of said aperture.

5. The combination with a liquid fuel tank adapted to contain liquid fuel under air pressure, of a fuel feeding mechanism for a burner comprising a valve body mounted in said tank and having an inlet and an outlet and a valve seat intermediate said inlet and outlet, a valve operable externally of said body and movable to and from said seat, an inner tube connected with and sealed to said valve at its upper end and running downwardly into the liquid fuel space of said tank, said inner tube being open at its lower end and having a discharge orifice spaced above its lower end, a medial tube connected with and communicating with the lower end of said valve body surrounding said inner tube in coaxial relation and having an apertured closure at its lower end located within the liquid fuel space of said tank, and through which aperture said inner tube

normally extends to fill the same, said closure being disposed slightly above the position of the lower end of said inner tube when said valve is seated and when said valve is partly but not fully raised from its seat, whereby when the valve is raised to its extreme position from said seat, said inner tube will be drawn upwardly above said closure, said medial tube having an air opening adjacent its lower end below the orifice of said in-

ner tube and means communicating said air opening with the air space of said tank.

6. The structure defined in claim 5, said means comprising an outer tube disposed in outer co-axial relation from said medial tube, sealed to said medial tube at its lower end and having an opening disposed within the air space of said tank.
